being had to the accompanying drawing making part of this Specification.

The design is that of a cotton bale in outline as shown at A. in the drawing, it is there represented as stamped or punched on the surface of a weeding hoe as a trade mark.

What we claim as our invention or production and desire to secure by Letters Patent is.

The design of a cotton bale as a trade mark as herein described.

In testimony whereof we have signed our names to this Specification before two subscribing witnesses.
